UNITED STATES PATENT OFFICE.

JAMES D. LALOR, OF BALTIMORE, MARYLAND, ASSIGNOR TO THE LALOR FUEL OIL SYSTEM COMPANY, INC., OF BALTIMORE, MARYLAND, A CORPORATION OF MARYLAND.

VALVE.

Application filed December 15, 1924. Serial No. 756,000.

This invention relates to valves, more particularly to a type which may be conveniently distinguished from others by the appellation of "non-siphonic".

Such valves are useful for example in liquid fuel feed systems to prevent oil from flowing from a gravity tank into a building should the line piping be fractured, as well as to automatically shut off the supply when the pumps—used in the system to force the fuel to the apparatus by which it is consumed—are stopped; or, in other words, to prevent siphonic action under any of the aforesaid conditions.

My invention is directed toward securing in a valve of the kind referred to, absolute surety and infallibility of action; extreme simplicity of design and construction; and reliability against derangement in long continued usage.

From the detailed description hereinafter of a typical embodiment of my invention, will be manifest how the desiderata above outlined may be readily attained; while the appended claims serve to concisely define those features which I believe to be novel and patentable.

With reference to the drawings, Fig. I is a sectional view of a valve conveniently embodying my invention.

Figs. II and III are detail sections taken, respectively, as indicated by the arrows II—II and III—III in Fig. I; and,

Fig. IV is a diagrammatic illustration showing one of the practical uses to which the valve of my invention may be put.

In these illustrations, the body or casing of the valve is comprehensively designated by the numeral 1, and comprises a flow channel with the inlet and outlet ends 2, 3 respectively, set apart by a partition 4; said casing being also characterized by a lateral offset 5 with an axial bore 6 open to the outlet side 3 of the channel. This offset 5 is shouldered and screw-threaded at 7 for removable attachment of a cap piece 8, which, together with the bore 6, constitute a domed chamber 9. The movable element of the valve 1 is in the form of a cylindric piston 10 whereof one end is disposed for guidance in the dome bore 6, while its opposite end extends through an orifice 11 in the intermediate straight portion 12 of the partition 4. The latter end of the piston 10 is hollow as

indicated at 13, and open to the inlet side 2 of the valve; while the wall surrounding the hollow 13 is provided with a ring of radial ports 14, which, when the piston 10 is in the position shown in Fig. I, are lapped by the partition 4 so as to close the flow channel 2, 3 against passage of fluid therethrough. As a means for yieldingly urging the piston 10 to this position, that end thereof which is disposed in the dome chamber 9 is acted upon by a helical compression spring 15, the same being held centralized and against undue sidewise flexure by an engaging axial stem 16 of said piston, free positional adjustment of the spring 15 being permitted through use of a bevel headed shoulder button 17 fitting the opposite end and bearing against the top wall of the cap piece 8. The closed position of the valve 1 is determined by a fixed stop pin 18 engaging an axial recess 19 within the hollow end 13 of the piston 10. As shown, the pin 18 is threaded as at 20 and screwed into a boss 21 projecting from the valve body 1, a polygonal head 22 at the exterior serving to facilitate its removal when necessary or desired.

In order that the dome chamber 9 may be at all times in communication with the outlet side 3 of the flow channel of the valve 1, that end of the piston 10 slidable therein is longitudinally grooved as at 23 to provide by-pass channels for this purpose.

In operation, it will be seen that when suction is applied to the outlet side 3 of the valve channel, the piston 10 will be shifted in opposition to the compression spring 15 by virtue of the access of said suction through the grooves 23 to that end of the piston within the dome chamber 9 so that the ports 14 are moved beyond (i. e. above with reference to the position of the valve in Fig. I) the partition 4 and thus uncovered to permit flow through the valve 1. Upon cessation of the suction, the spring 15 acts immediately to automatically shift the piston 10 to the closed position illustrated so as to intercept further flow through the valve 1.

As previously stated, the valve 1 of my invention is especially useful in connection with a fuel feed system for oil burning installations. To make its function clear in this connection, I have represented such an installation diagrammatically in Fig. IV wherein the valve 1 is shown as interposed

in a pipe line L leading from an exterior gravity supply tank T to a pump P within a building B containing—on different floors or levels—the furnaces or other apparatus 5 to which the fuel is to be supplied under pressure. In responding to the suction or lift of the pump P, the piston 10 of the valve 1 will shift to open position with the ports 14 uncovered for passage of the fluid. 10 When the pump P is stopped and the suction or lift ceases, the piston 10 will, under 70
urgency of the spring 15, automatically shift to closed position as already explained, the spring 15 being so designed as to be capable 15 of overcoming with a slight excess, the head pressure of the fluid in the tank T. In the event of a leak or fracture in the pipe line L, the valve 1, it will be seen, prevents the oil from the tank T siphoning or flowing into 20 the building B, yet permits the pump P to feed the necessary quantities of oil to the apparatus therein. The valve of my invention thus not only serves to obviate gross wastage of fuel under such contingencies, but also 25 acts as a safe-guard against fire.

Having thus described my invention, I claim:

1. A valve comprising a casing affording a flow channel; a partition extending across 30 the channel with an intermediate straight portion having an orifice therethrough; a dome chamber open to the outlet side of the channel; and a hollow-ended piston—having lateral ports affording flow passages 35 therethrough,—slidably guided in the dome chamber, with the hollow end thereof extending through the orifice of the partition; said piston having longitudinal grooves affording communication at all times with the 40 outflow side of the channel and responsive to suction in the dome chamber for maintenance in open position with the ports therein uncovered to permit flow through the valve, and in the absence of suction, to automatically shift so that said ports are brought 45 into lapping relation with the partition to intercept flow through the valve.
  2. A valve comprising a casing affording a flow channel; a partition extending across 50 the channel with an intermediate straight portion having an orifice therethrough; a dome chamber open to the outlet side of the channel; and a hollow-ended piston having a ring of lateral ports affording flow passage 55 therethrough with its exterior surface—beyond said ports—longitudinally grooved to afford communication at all times with the outflow side of the channel and slidably guided in the dome chamber, the hollow end
- of said piston extending through the orifice 60 in the partition; said piston being adapted to respond for maintenance in open position with the ports therein uncovered to permit flow through the valve, to suction at the outlet side of the channel communicated to 65 the dome chamber via the longitudinal grooves, and in the absence of such suction to shift so that said ports are brought into lapping relation with the partition to intercept flow through the valve. 70
3. A valve comprising a casing affording a flow channel; a partition extending across the channel with an intermediate straight portion having an orifice therethrough; a dome chamber open to the outlet side of the 75 channel; a hollow-ended piston having a ring of lateral ports affording flow passages therethrough with its exterior surface—beyond said ports—longitudinally grooved and slidably guided in the dome chamber, 80 the hollow end of said piston extending through the orifice in the partition, said piston being adapted to respond, for maintenance in open position with the ports therein uncovered to permit flow through the 85 valve, to suction at the outlet side of the channel communicated to the dome chamber via the longitudinal grooves; and a spring within the dome chamber functioning in the absence of suction, to automatically shift the 90 piston so that said ports are brought into lapping relation with the partition to intercept flow through the valve.
4. A valve comprising a casing affording a flow channel; an orificed partition extending across the channel; a dome chamber open to the outlet side of the channel; a laterally-ported piston with one end thereof longitudinally grooved and slidably guided in the dome chamber, and the other end thereof extending through the orifice of the partition, 95 said piston being adapted to respond, for maintenance in open position with the ports therein uncovered to permit flow through the valve, to suction at the outlet side of the 100 channel communicated to the dome chamber via the longitudinal grooves; a spring within the dome chamber functioning in absence of suction, to automatically shift the piston so that said ports are brought into lapping relation with the partition to intercept flow 105 through the valve; and a stop pin engaging an axial recess in the piston to determine the extent of such shifting.

In testimony whereof, I have hereunto signed my name at Baltimore, Maryland, this 12th day of November, 1924.

JAMES D. LALOR.
